UNITED STATES PATENT OFFICE.

HAAKON SUSERUD, OF MONTREAL, QUEBEC, CANADA.

FLASH-LIGHT CARRIER.

1,245,817.

Specification of Letters Patent.

Patented Nov. 6, 1917.

Application filed March 2, 1917. Serial No. 152,122.

To all whom it may concern:

Be it known that I, HAAKON SUSERUD, a subject of the King of Norway, residing at Montreal, in the Province of Quebec and 5 Dominion of Canada, have invented certain new and useful Improvements in Flash-Light Carriers; and I do hereby declare the following to be a full, clear, and exact 10 description of the invention, such as will enable others skilled in the art to which it appertains to make and use the same.

This invention relates to new and useful 15 improvements in flashlight carriers, and the principal object of the invention is to provide a convenient means for holding a flashlight in operative position for the user during the process of writing.

Another object of the invention is to provide a device which may be attached to the 20 thumb in order that when the user is holding a pencil the light may be directed to the point desired.

Another object of the invention is to provide a device which may be strapped to the 25 wrist of the user and when not in use is provided with a pocket into which the lamp bulb, socket and wire may be placed.

A still further object of the invention is to provide an adjustable strap for surrounding 30 the thumb of the user which firmly secures the lamp bulb in place.

With these and other objects in view, the invention consists in the novel combination and arrangement of parts which will be 35 fully set forth in the following specification and accompanying drawings, in which:—

Figure 1 is a view of a hand showing the device applied thereto;

Fig. 2 is a view showing the device in 40 open position showing the lamp bulb and socket placed in their respective compartments;

Fig. 3 is a sectional view through the battery carrier showing the space for the 45 spare lamp and the pocket for the reception of the lamp socket and wire; and

Fig. 4 is a detail perspective view of the thumb band for securing the lamp socket in place.

50 Referring to the drawings, 1 designates the back of the device having secured thereto intermediate its ends the side walls 2 of the battery pocket 3. The front wall 4 of the battery pocket is formed integrally with the 55 side walls and the bottom wall 5 of said pocket is formed integrally with the front

and rear walls. It will thus be seen that the device may be stamped out of a single blank of material if so desired. Formed on one side of the pocket 3 is a flap 6 which is folded back to form a pocket 7 as illustrated in Fig. 3, for the reception of the spare bulb so that in case the bulb in use should burn out another bulb may be substituted therefor. Formed on the side of 60 the back or body 1 of the device opposite that having a flap 6 formed thereon, is a flap 8 provided with a tongue 9 carrying one-half of a snap fastening 10 while the other half of said fastening is secured to 65 the outer side of the wall 4. The flap 8 when in closed position forms a pocket for the reception of the lamp bulb and socket and the wires, together with the thumb band by which it is supported in use. 75

A suitable closing flap 11 is formed on the upper edge of the body 1, and is provided with one-half of a snap fastener 12 which cooperates with the other half of the snap fastener which is secured to the 80 outer side of the front wall 4. A notch 13 is formed in the edge of the flap 11 adjacent the point where it joins the body 1 and on the side of the body having a flange 8 formed thereon, and this notch is adapted to accommodate the connection wires by means of which the lamp socket is connected to the battery.

As shown in Fig. 2, the battery is placed in position within the pocket 3 and suitable 90 wires 14 lead from the terminals of the battery through suitable eyelets 15 secured in apertures of the flap 11 and are connected to the socket designated by the numeral 16 into which a lamp bulb 17 is adapted to be 95 threaded. Surrounding the wires 14 adjacent the socket is the thumb band which will be more fully hereinafter described.

The thumb band previously referred to is best illustrated in Fig. 4 and comprises a 100 main body 18 provided adjacent opposite ends with transverse slots 19 and 20. A tongue 21 is formed on the end of the body adjacent the slot 19 and this tongue is of a width substantially equal to the width of the 105 slot so that it may be looped around as illustrated in Fig. 4 and passed through the slot to provide a wire retaining loop through which the conductor wires from the battery to the lamp socket extend. The 110 tongue 21 is provided adjacent its free end with a plurality of notches forming shoul-

ders 22 and the end of the tongue is adapted to be extended through the slot 20 so as to form a loop for surrounding the thumb of the user as illustrated in Fig. 1.

- 5 In order to secure the device to the wrist of the wearer, a suitable wrist encircling strap 23 is sewed or otherwise secured to the wall 1 and carries a plurality of snap fasteners 24 arranged in spaced relation so 10 that the device may be fitted to wrists of different sizes.

It will be apparent from the foregoing, that in use the device is secured to the wrist in the manner illustrated in Fig. 1 while the 15 thumb band is secured around the thumb and thus the lamp socket will be supported adjacent the end of the thumb. Upon tightening the lamp bulb within the socket it will be seen that the current will flow from the 20 battery to the wires into the socket and through the lamp, thereby causing the lamp bulb to glow. It will be also apparent that in the use of a device of this kind the free use of the thumb and all the fingers is had, 25 so that writing is easily accomplished and the light is concentrated at the point desired.

While in the foregoing there has been shown and described the preferred embodiment of this invention, it is to be understood that such changes may be made in the combination and arrangement of parts as will fall within the spirit and scope of the appended claims.

35 What is claimed is:—

1. A device of the class described, comprising a back, front, side and a bottom wall forming a pocket, a battery within the pocket, a flap for closing the pocket, conductor wires extending through said flap and connected with the battery, a lamp socket at the end of the wires, a lamp bulb mounted in said socket and a flap formed on one side of the pocket to form a pocket when 40 closed to receive the lamp bulb and socket.
- 45

2. A device of the class described, comprising a back, front, side and a bottom wall forming a pocket, a battery within the pocket, a flap for closing the pocket, conductor wires extending through said flap and connected with the battery, a lamp socket at the end of the wires, a lamp bulb mounted in said socket and a flap formed on one side of the pocket to form a pocket when closed to receive the lamp bulb and socket, and means 50 for supporting the lamp bulb and socket on the thumb of the user.

3. A device of the class described, comprising a back, front, side and a bottom wall forming a pocket, a battery within the 60 pocket, a flap for closing the pocket, conducting wires extending through said flap and connected with the battery, a lamp socket at the end of the wires, a lamp bulb mounted in said socket and a flap formed on one side of 65 the pocket to form a pocket when closed to receive the lamp bulb and socket, means for supporting the lamp bulb and socket on the thumb of the user, and means to support the pocket and battery on the wrist of the user. 70

4. A device of the class described, comprising a back, front, side and a bottom wall forming a pocket, a battery within the pocket, a flap for closing the pocket, conductor wires extending through said flap and connected with the battery, a lamp socket at the end of the wires, a lamp bulb mounted in said socket and a flap formed on one side of the pocket to form a pocket when closed to receive the lamp bulb and socket, 75 and an adjustable band for surrounding the thumb of the user, said band being adapted to support the lamp socket on the thumb of the user.

In testimony whereof I affix my signature 85
in presence of two witnesses.

HAAKON SUSERUD.
